UNITED STATES PATENT OFFICE.

ALEXANDER BAIN, OF NEW YORK, N. Y., ASSIGNOR TO WM. H. ALLEN, OF SAME PLACE.

IMPROVEMENT IN CALLS FOR TELEGRAPHS.

Specification forming part of Letters Patent No. 38,529, dated May 12, 1863; antedated December 11, 1862.

To all whom it may concern:

Be it known that I, ALEXANDER BAIN, of the city, county, and State of New York, have invented a new and Improved Call for Electric Telegraphs; and I do hereby declare that the following is a full, clear, and exact description of the same, reference being had to the accompanying drawings, forming part of this specification.

Figure 1 is a top view of the improved call, which I term the "silent message call." Fig. 2 is a central vertical section of the same.

Similar letters of reference indicate corresponding parts in both figures.

The custom now generally adopted in this country in electric telegraphy of reading intelligence by the sounds emitted by the instruments in their operation has rendered it difficult, if not impracticable, with the instruments at present in common use, to transmit intelligence with any degree of secrecy, for the instruments in all other offices or stations on a line of telegraph besides that to which the intelligence is to be transmitted, operating in unison with the instrument or instruments at that station, produce the same sounds, which may be heard by other persons than the confidential operator who may be familiar with the telegraphic alphabet and near the instrument or instruments. I have in a great measure obviated this difficulty by means of the receiving instrument which constitutes the subject-matter of Letters Patent No. 1,850, dated July 23, 1861, but it is essentially necessary that these several offices or stations on a line should have means of communicating with each other by sounds audible at some considerable distance from the instruments, so that the operator at one office or station may draw the attention of him at any other which it may be wished to communicate with; and to this end this invention consists in an instrument which, I term the "silent message call," from which, though it is capable of calling the attention of the operator, messages cannot be read, because the electric pulsations produced in their transmission are too frequent for its action, but which, when the pulsations are less frequent, will act in accordance with them, and

thereby produce sounds sufficiently loud to be heard at a distance greater or less, according to the strength of the electric currents, and which sounds will then be intelligible and are intended to be used to "call" from one office or station to another.

To enable others skilled in the art to make and use my invention, I will proceed to describe its construction and operation.

A is a wooden stand having secured to it, one above another at a short distance apart, by pillars C C, two oblong reels or frames, B B, which are made of hard india-rubber or other suitable non-conducting material covered or filled with coils of fine copper wire covered with silk, and which resemble those commonly used in galvanometers.

E is a permanent steel-bar magnet, secured at the middle of its length on a horizontal axle, a, which is arranged to oscillate freely in bearings provided for it in two fixed pillars, F F, secured to the stand A on opposite sides of the reels B B, the said magnet being situated within the reels and the said axle between the two reels.

Attached to the permanent magnet E is a weight, e, composed of a piece of wire, which is bent to a position to compensate for the dip of the magnet and balance it in a horizontal position when not influenced by currents of electricity passing through the coils of wire on the reels.

G is a glass disk secured above the reels by a screw, c, passing through its center to a cross-bar, H, which is arranged across the upper reel, and whose ends are secured on the tops of the pillars F F.

I I are the terminal screws for connecting the ends of the telegraph-conductor to the instrument. Two of the ends of the reel-wires are secured together, and the other ends are secured to the terminal screws I I, one to each screw.

It will be observed that the permanent magnet E is placed in the same position as what is known as a "dipping needle"—that is to say, the axle and the magnet are both in the same horizontal plane—so that when the needle is deflected by the electric current passing

through the wires on the reels one end of the magnet rises while the other descends; hence it follows that in whichever direction the currents pass through the wires on the reels, provided the electric currents or pulsations are of sufficient duration, one end or the other rises and strikes the glass disk, and thereby produces an audible sound.

In telegraphing the message currents pass through the coils of wire on the reels, but the duration of such currents and the intervals between them being very short, the magnet cannot complete its range of motion, partly on account of the influence of the magnetism of the coils extending over a much greater range than that of an ordinary electro-magnet, such as is ordinarily used for telegraphic purposes, whose chief magnetic power is at or close to the poles. Therefore the instrument, though it serves well enough as a call, will not make

known any of the ordinary telegraphic communications.

This call is to be so arranged in the office or station in relation to the receiving-instrument, and with a brake so applied in connection with the two, that when the receiving-instrument is not desired to be in operation the latter may be shut off the circuit, the call being in the meantime allowed to remain in circuit.

What I claim as my invention, and desire to secure by Letters Patent, is—

The call composed of the reels of wire B B, the permanent magnet E, and the glass disk G, or its equivalent, the whole combined, applied, and arranged to operate substantially as and for the purpose herein specified.

ALEXANDER BAIN.
